UNITED STATES PATENT OFFICE

117,909

DESIGN FOR A SHOE LAST

Christy Reggie, Queens Village, N. Y.

Application July 19, 1939, Serial No. 86,075

Term of patent 7 years

To all whom it may concern:

Be it known that I, Christy Reggie, a citizen of the United States of America, residing in Queens Village, Long Island, county New York and State of New York, have invented a new, original, and ornamental Design for a Shoe Last, of which the following is a specification, reference being had to the accompanying drawing, forming part thereof.

Fig. 1 is a top perspective view of a shoe last showing my new design.

Fig. 2 is a side perspective view thereof.

I claim:

The ornamental design for a shoe last, substantially as shown.

CHRISTY REGGIE.
